HAIR DRIER

Frederick M. Crook and Eugene Caster,
Kansas City, Mo.

Application December 26, 1931, Serial No. 583,196

4 Claims. (Cl. 34—26)

This invention relates to hair drying apparatus of the type including hoods for directing heated dry air over the hair of the person seated beneath the hood.

5 The principal objects of the invention are to effect adjustment of a hood of hair drying apparatus to heads at different elevations and to assure and accelerate proper distribution of heated dry air through portions of the mass of hair of 10 the subject.

Other objects of the invention will be apparent in the course of the following description of one form of apparatus embodying the invention and illustrated in the accompanying drawings where- 5 in:

Fig. 1 is a perspective view of apparatus constructed in accordance with the invention illustrating three customers to whose heads of hair three of the hoods are adjusted.

0 Fig. 2 is an enlarged view of portions of the heater, fan casing, conduits and air distributing members including a branch pipe having a hood attached thereto, the parts being shown partly in section and partly broken away, and illustrating the adjustable mounting of the tubular stem 5 of a hood on a branch pipe.

Fig. 3 is a further enlarged section through the apex of one of the hoods and giving a perspective view of the end portion of the branch pipe and a conical deflector located at the apex 0 of the hood.

Fig. 4 is a section on the line 4—4, Fig. 6, illustrating the valve controlling flow of air through the branch pipe toward the hood.

5 Fig. 5 is an enlarged fragmentary perspective view of telescoping stem and branch pipe portions, partly in section and partly broken away.

Fig. 6 is a vertical section through the adjacent ends of the branch pipe portions and the 0 valve, a hood-retracting spring being shown fragmentarily.

Referring more in detail to the drawings:

10 designates a conduit mounted on posts 12 and formed of sections 14, each provided with 5 downwardly projecting branch pipes including upper and lower sections or portions 16 and 17 for supporting hoods 18 in approximately the proper position for discharging heated dry air to the hair of customers seated below the hoods, as later described. The upper portions 16 of the branches are preferably made integral with the sections, for example by welding, and convex walls 20 connecting the pipes to the sections form curved edges over which air may move into the branches.

The outer end of the conduit is closed and the inner or right hand end in Fig. 1 is connected to a fan housing 22 having an inlet pipe 24 connected to a heater 26 supported on a skeleton frame including legs 28. The conduit thus forms a manifold for distributing air to the branches. 5

The heater 26 includes a vertically positioned inner drum 30 having an imperforate upper end wall 32. Transverse header plates or walls 34 and 36 are located respectively in a position spaced slightly from the end wall 32 and at the lower end of the drum, thus forming a flue chamber 38 at the upper end of the drum and a second larger air chamber between the two headers. 10

Tubes 40 having opposite open ends mounted 15 in openings 41 in the headers conduct a heating medium through the larger chamber, a heating element such as a gas burner 43 being mounted on a suitable bracket 44 below the drum to supply the heating condenser. 20

The vertical walls of the inner drum 30 are preferably extended taperingly downwardly to provide imperforate walls for supporting the burner bracket, and form a housing for the burner. Air is thus drawn by the operation of 25 the heater through the bracket into the tubes 40. A second drum 45 surrounds the first named drum in spaced relation therewith to hold insulation between the drums. The double-walled heater includes wall portions 46 and 47, Fig. 1, the portion 46 being provided with a screened air inlet port 48 whereby the air chamber communicates with atmosphere and with a gas outlet port 49 from the chamber 38 provided with a flue 50. The wall portion 47 has an opening 52 to which 30 the fan inlet pipe 24 is connected. 35

The portions 16 and 17 of each branch pipe are connected by a collar 54 mounted on the lower end of said upper portion 16 and fixed thereto by fasteners such as rivets 55, the lower end edge of the pipe portion 16 registering with the lower end edge of the collar. 40

Extending outwardly radially from the lower end of the cylindrical collar 54 is a bracket-like flange or wing plate 56 having width slightly 45 greater than the external diameter of the collar and a lower face lying substantially in the plane of the lower end edge of the pipe portion 16 and at right angles to the axis of said pipe portions, to form the upper side of a casing or guide for 50 a sliding plate valve as presently described.

A circumferential external boss 58 formed at the upper end of the branch pipe portion 17 has an end face in the plane of the upper end edge of said pipe portion, and an outwardly off- 55

set segmental portion of the boss is extended upwardly to form a rim 60 against which a peripheral portion of the end of the collar 54 abuts, as shown in Fig. 6. A groove-like seat 62 is thus formed at the upper end of the pipe portion 17.

A plate flange or wing 64 similar to the wing 58 and extending radially from the boss 58 at the open side of the rim 60 has an upper face 10 registering with the seat 62, and is provided with upstanding spaced edge flanges or rail portions 65 and 66 forming continuations of the rim 60 and engaging the peripheral portion of the plate 64.

15 Suitable means are provided for securing the branch pipe portions together and sealingly connecting the valve casing members, such as ears 67 on the boss and wing 64 apertured for passing bolts therethrough into similar ears on the 20 collar 54 and upper plate 56.

The rim 60 and rail portions 65 and 66 thus space the wings and form the retaining wall or guides of a casing for a plate valve 68 slideable on the lower wing into and out of position to 25 close the passage through the branch pipe, as best shown in Fig. 4.

The valve has an arcuate recess 70, and the rounded end 72 of a valve operating lever 74 pivoted at 76 to the wing 64 operates in the 30 recess on the valve. The lever projects outwardly from the casing through a slot 78 formed by the spacing of the rail portions 65 and 56.

A tube or sleeve 80, slidably mounted over each 35 of the branch pipe portions 17, is fixed to a corresponding hood and held against separation from the branch pipe as later described. A short internal longitudinal rib 81 at the upper end of the sleeve slides in a limited longitudinal external groove 82 formed in the branch pipe 17, and conforming to the angular cross section of 40 the groove to key the pipe and sleeve against rotation relatively to each other. A longitudinal groove 83 diametrically opposite the groove 82 forms a track for the rounded end of a set screw 84 threaded in a boss 86 of the hood sleeve. The screw may be moved into frictional engagement 45 with the wall of the groove 83 to latch the hood sleeve at a selected position on the branch pipe portion 17.

50 The grooves preferably comprise portions of the pipe wall impressed to confer desired cross sections on the grooves.

The upper end of the sleeve is provided with a peripheral collar-like boss 87 having an internal annular groove to accommodate packing 55 88 for sealing the joint between the movable sliding sleeve and the pipe portion 17 as shown in Figs. 2 and 5.

The lower end of the sleeve 80 flares as best 60 shown in Fig. 3, and has a lower end edge or flat rim portion 89 overlying the flattened apical portion of the dome-like hood 18 around the apical opening 90 in the hood. The rim portion 89 is fixed to the apical portion of the 65 hood by suitable fasteners such as rivets or bolts 91.

The wall of the hood curves outwardly from 70 the apical portion and then has substantially cylindrical form to the peripheral edge or rim, thus forming a flaring inner surface. A separate rim 92 is preferably provided having an inner edge abutting the lower edge of the hood and having ears 93 overlying the inner surface of the hood whereby bolts may be mounted in 75 registering openings of the hood and ears for

securing the rims to the hood. The rim is curved inwardly throughout the periphery of the hood edge, and then curved retractive to form guard rails or deflectors for turning air currents laterally and upwardly toward the top of the subject's head and the apex of the hood.

5 In order to distribute heated dry air more effectively into and through the hood and through the hair, the hood is further provided with a baffle or deflector 94 comprising a circular conical block having a convex upper surface and provided with a plurality of annularly disposed openings or bores 96 having axes inclined slightly downwardly inwardly with reference to the axis of the baffle as shown in Fig. 2. Wings or strips 98 attached to the edge of the block at the base thereof pass divergently upwardly through the opening 90 and have upper ends fixed to the flaring portion of the sleeve by suitable means such as welding.

Attention is called to the vertical spacing of the 20 apex of the conical baffle from the upper end of the hood, the location of the axis of the baffle in the axis of the hood, and the lateral spacing of the base edge of the baffle from the edges of the hood inlet opening 90. The bores 96 are angular 25 to the convex face and axis of the baffle and the sleeve is inclined to the axis of the hood, and the base of the baffle is parallel with the flattened apical end of the hood.

The means above referred to for retaining the 30 hood sleeves in operating relation with the related branch pipes includes in each instance a screw 100 removably fixed to the pipe at the lower open end of the groove 82 to engage the lower end of the rib 81 when the sleeve has been 35 extended a substantial distance.

A spring 102 has a lower end anchored to an ear 104 on the apex of the conical deflector and extends upwardly through the sleeve and branch pipe portion 17 to a bar 106 mounted in recesses 40 108 formed in the seat 62 as best shown in Fig. 2.

The spring is thus anchored to the hood and to the fixed branch pipe, and tends to return the sleeve and hood to and hold the same in retracted position. A handle 110 is fixed to a boss 112 45 on the sleeve for extending the hood.

The result of the structure illustrated is that air currents tend chiefly to move toward the back or depressed portion of the hood as shown in Fig. 3, and are largely deflected into this portion by 50 the baffle. Some of the currents however are deflected toward the front portion of the hood, and relatively small amounts of air may pass through the bores of the baffle toward the top of the subject's head.

The crown of the head is, however, largely shielded from direct currents by the baffle, and currents are restricted even when passing through the baffle due to the angular relation between the axes of the sleeve and baffle.

60 It will be particularly noted that we have provided our hood with a portion which fits the nape of the neck and thereby prevents loss of air at this point to a great extent.

65 What we claim and desire to secure by Letters Patent is:

1. In apparatus of the character described, a pipe having a longitudinal groove, a hood having a stem sleeved on the pipe and provided with an 70 internal rib moving in said groove, means movably mounted on the stem for frictionally latching the sleeve to the pipe to retain the hood in adjusted relation with the pipe, and means mounted on the pipe in one end of said groove 75

forming a stop to limit movement of the rib in one direction.

2. In a hair drying device, a vertical air conducting tube, a hood secured to the tube in angular relation thereto having an apical opening in communication with the hood and having a nape fitting portion, and a deflector disk carried by said tube in angular relation to the axis thereof and spaced below the apical opening for deflecting the major portion of the air downwardly toward said nape fitting portion.

3. In a hair drying device, a vertical air conducting tube terminating at its lower end in an outwardly flaring rim portion in angular relation to the tube, a hood having a nape fitting portion and a flattened apical portion provided with an opening registering with the tube, means for securing said rim portion to the flattened portion of the hood, and a deflector associated with the opening and in parallel relation to said rim and

offset laterally from the axis of the tube for deflecting the major portion of the air downwardly toward said nape fitting portion.

4. In an apparatus of the character described including a hood having a downwardly curved wall adapted to cover a head of hair of a person and having an air inlet, means for delivering heated air to the interior of the hood through said inlet, a deflector disk having approximately the diameter of said air inlet in the hood, means supporting the deflector disk below said inlet for directing the air for travel downwardly in guided contact with said wall, and a deflector member carried by the wall and having an upwardly curved deflecting portion for deflecting the air travelling down the wall upwardly through the hair in the direction of said deflector disk.
